F. PRINZ.
ECCENTRIC BALL BEARING RECIPROCATING DEVICE.
APPLICATION FILED JAN. 21, 1915.

1,162,512.

Patented Nov. 30, 1915

UNITED STATES PATENT OFFICE.

FAUSTIN PRINZ, OF MILWAUKEE, WISCONSIN.

ECCENTRIC BALL-BEARING RECIPROCATING DEVICE.

1,162,512.

Specification of Letters Patent. Patented Nov. 30, 1915.

Application filed January 21, 1915. Serial No. 3,523.

To all whom it may concern:

Be it known that I, FAUSTIN PRINZ, a citizen of the United States, residing at Milwaukee, in the county of Milwaukee and State of Wisconsin, have invented certain new and useful Improvements in Eccentric Ball-Bearing Reciprocating Devices; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to shaking screens for grain and like separators, and particularly to means for reciprocating the shaker or screen.

It has for its object to provide an improved eccentric and ball-bearing box for imparting the reciprocating motion to the shaker or screen so that a smooth, easy and regular movement of the screen is obtained and wherein both the ball-bearings and the eccentric are clamped in place by means preventing the displacement of either the eccentric or ball-bearings.

It also consists in features of construction in various parts of the eccentric ball-bearing retaining box having functions hereinafter mentioned for the parts.

To the accomplishment of the foregoing and such other objects as may be made hereinafter to appear, the invention consists in the features hereinafter particularly described and then sought to be clearly defined by the claims, reference being had to the accompanying drawing forming a part hereof, and in which—

Figure 1 is a side elevation of the eccentric box with one side removed and showing the pusher-arm; Fig. 2 is a horizontal section through the eccentric box and pusher-arm. Fig. 3 is a side view of the device, on a smaller scale than the other figures.

In the drawing, the numeral 1 designates a strap forming one part of the eccentric box and having a screen pusher-arm 2 formed with a hook 3 with which will engage one end of a rod extending to the other end of the shaker or screen where it is provided with a spring and nut and connected with the screen but which details are not shown as they do not constitute the present invention.

To opposite sides of the strap 1 are secured by threaded bolts 4 and nuts 5 side plates or cheeks 6 which have inwardly projecting flanges 7 which bear against the inner face of the strap 1 as shown in Fig. 2. These constitute the sides of the box and form an interior hollow space or chamber 8 in which is positioned the concentric rings 9 and 10 constituting the annular rim-way or race for the balls 11 interposed between the two rings; the ring 9 having a tapered interior and formed on its exterior with cavities 12 for the balls, and the ring 10 having a concave interior face against which the balls bear, the exterior of the ring bearing against the interior face of the strap 1.

The numeral 13 designates a split eccentric which encircles the rotatable drive shaft 14, and around the eccentric is a sleeve 15 which has a tapered or beveled exterior bearing against the tapered interior of the race-ring 9, and formed with a threaded end 16 upon which is screwed a nut 17. By screwing up this nut the tapered sleeve is caused to wedge the race-rings in place and at the same time clamp the eccentric to its shaft so that the tapered sleeve and its nut perform the two-fold function mentioned and hold the eccentric and the race-rings and their balls securely in place and proper position for the efficient reciprocation of the shaker or screen through the connection of the strap pusher-arm therewith.

To insure the eccentric being correctly mounted or adjusted on its shaft for the proper reciprocation of the screen, a pin 18 enters a recess or socket in the drive shaft and into a corresponding socket in the eccentric thus insuring the proper positioning of the eccentric and holding it in such position while clamping the parts in place by the tapered sleeve and its nut.

The chamber 8 serves to receive a suitable lubricant for the ball-bearings; and forming stuffing boxes to keep the lubricant from working its way out of the box, the inner ends of the side plates or cheeks 6 are formed with cavities 19 to receive a suitable packing, and plates 20 secured to the cheeks by bolts 21 and nuts 22 serve as covers to keep the packing in the cavities.

The construction described constitutes a very efficient ball-bearing eccentric for reciprocating the shakers or sieves of a separator, easy and smooth in operation and possessing the advantages of comparatively

few parts and their easy assemblage; a secure clamping and holding of the eccentric together with the balls and their race-rings in place, and protection of them and their lubricant from exposure.

Having described my invention and set forth its merits, what I claim is:

1. An eccentric ball-bearing reciprocating device comprising a drive-shaft, a split eccentric mounted on the shaft, a box encircling the eccentric, a ball-bearing race ring mounted within the box, one face of the race ring being tapered, a sleeve encircling the eccentric and having a tapering exterior engaging the tapered face of the ball-bearing race ring, and a nut threaded onto the sleeve for clamping both the eccentric and the ball-bearing race ring in place.

2. An eccentric ball-bearing reciprocating device comprising a drive-shaft, a split eccentric mounted on the shaft, a strap with a power transmitting arm extending therefrom, cheeks attached to opposite sides of the strap and having inwardly extending flanges next to the inner face of the strap and forming a chamber between the strap and eccentric, ball-bearing race rings within the chamber, one of which bears against the inner face of the strap and the other of which is formed with a tapered inner face, a sleeve encircling the eccentric and having a tapered outer face bearing against the tapered face of the adjacent race-ring, and a nut threaded onto the sleeve to clamp the eccentric and the race-rings in place.

3. An eccentric ball-bearing reciprocating

device comprising a drive-shaft, a split eccentric mounted on the shaft, a box encircling the eccentric and having an interior chamber for a lubricant, a ball-bearing race ring mounted within said chamber, one face of the race ring being tapered, a sleeve encircling the eccentric and having a tapering exterior engaging the tapered face of the ball-bearing race ring, a nut threaded onto the sleeve for clamping both the eccentric and the ball-bearing race ring in place, the sides of the box next to the eccentric being formed with packing receiving cavities, and replaceable covers for closing said cavities and permitting access thereto.

4. An eccentric ball-bearing reciprocating device comprising a drive-shaft, a split ring mounted on the shaft, a box encircling the eccentric, a ball-bearing race ring mounted within the box, one face of the race ring being tapered, a sleeve encircling the eccentric and having a tapering exterior engaging the tapered face of the ball-bearing race ring, a nut threaded onto the sleeve for clamping both the eccentric and the ball-bearing race ring in place, and a pin fitting in corresponding sockets in the shaft and eccentric to insure proper relation between the eccentric and the other parts.

In testimony whereof I affix my signature in presence of two witnesses.

FAUSTIN PRINZ.
